UNITED STATES PATENT OFFICE

JOHN MUELLER, OF CLEVELAND, OHIO.

SELF-CLOSING FAUCET.

1,024,094.

Specification of Letters Patent.

Patented Apr. 23, 1912.

Application filed September 25, 1911. Serial No. 651,017.

To all whom it may concern:

Be it known that I, JOHN MUELLER, citizen of the United States, residing at Cleveland, in the county of Cuyahoga and State of Ohio, have invented certain new and useful Improvements in Self-Closing Faucets, of which the following is a specification.

This invention relates to self-closing faucets, and the object of the invention is to 10 prove the construction and operation of such faucets in certain important particulars as hereinafter fully described.

Referring to the accompanying drawings, Figure 1 is a vertical sectional elevation of 15 a faucet embodying my improvement, and Fig. 2 is a sectional elevation at right angles to Fig. 1. Fig. 3 is a detail of the handle, and Fig. 4 is a detail of the screw cap.

The physical embodiment as thus shown 20 comprises a faucet body B of a common pattern or style and which has the usual valve seat b and valve v to seat thereon. The said valve has a stem 2 of a length adapted to extend through and above the screw cap C, 25 where it is engaged by handle h, and said cap is threaded and screwed into or upon the top of body B and has an internal cavity open from below and filled with a suitable packing 3 about said stem to prevent leakage. A spiral wire spring S is interposed 30 about said stem between the valve and the said cap and a collar or washer 4 on said stem next beneath said packing serves as the upper bearing for said spring and has 35 a slight flange about its edge bearing against said cap as shown and serving to limit the expansion of the spring in that direction. Up to this point no actual novelty is claimed 40 for the parts as thus generally related, but both said cap and said handle are possessed 45 of novel features of construction which materially improve the operation of the faucet and distinguish it from others as an article of manufacture as will presently be seen. Thus, in the general style of faucets to 50 which this invention is related the pivot connection between the handle or lever corresponding to present handle h and valve stem 2 has always been so far above the bearing or fulcrum for the handle that the first effect 55 of the movement of the handle to open the valve is to draw the top of the valve stem laterally and bind the same frictionally against the cap, which made operation difficult and caused a rapid wearing away of the parts and consequent leakage. To further

illustrate, what I mean by the comparison, let it be supposed that the valve rod extends some distance above the top of the cap and that the pivot hole for the handle is in the top of said rod. The handle would be built to pivot through said hole and the fulcrum thereof would be on the top of the cap some distance below the said pivot point. This would inevitably cause a lateral pull on the top of the valve rod or stem before any lifting at all occurred and after that the lift had to be against this binding effect on the said rod and with inevitable lateral slipping of the handle on its fulcrum to obtain a lifting movement and opening of the valve.

Now, as a matter of fact, the faucet just described is the one upon which the present invention is an improvement and the faults or defects in which the present invention is 60 designed to overcome and remedy. This is accomplished by such a material change in construction that the pivot between the lever or handle h and the valve stem is in fact 65 very slightly beneath the fulcrum of the lever when the parts are normal, and such 70 that when the valve is say half way open the pivot and the fulcrum will be on the dead center or level and when fully open only as far above said center as it is below to begin 75 with. This enables the handle to be operated without any slipping whatever on its fulcrum and absolutely prevents side or friction pressure or binding in the valve 80 stem. Now, to these ends I provide the said 85 cap with two upright lugs 5 on its top on opposite sides of the bore therein for rod 2 and construct the head of handle h with a cavity or recess from beneath and with side 90 ears or flanges 8 having a pivot hole 10 through the same and extending on the outside 95 of said lugs but remaining out of touch with the surface 7. The pivot pin d for the valve stem is engaged through said holes 10 as shown. Between the said flanges and at 100 opposite sides of the said cavity the handle has flat bearing surface 9 resting down on said lugs when the parts are at rest, and the said lugs constitute the fulcrum upon which 105 the said handle is operated. In any case the handle rests exclusively on these lugs and the valve can be opened by either depressing or raising the handle. The natural and easy way is to depress it and in either case there is no lateral pull on the valve stem nor sliding on the fulcrum and the lift is directly 110 and only upward on easy and natural lines.

The spring S restores the valve to its seat after an operation, and a shoulder 6 on stem 2 is adapted to engage collar 4 and limit the upward movement of the stem and consequently the play of the handle.

What I claim is:

1. A faucet body and a cap thereon having an axial bore and studs at its top at each side of said bore, a valve stem extending 10 through said cap between said studs and a handle pivotally engaged with said stem and operatively seated on said studs, the plane of connection between said handle and said valve stem being just beneath the top of said studs, whereby direct lift of the 15 valve stem is promoted.

2. In self-closing faucets, a faucet body and a cap thereon having upward projections on its top, a lever handle having a head with side flanges provided with transverse holes and adapted to rest on said projections between said flanges, a valve stem having a hole coincident with the holes in said flanges and a pivot pin connecting the handle and stem through said holes a slight 20 distance beneath the top of said projections.

In testimony whereof I affix my signature in presence of two witnesses.

JOHN MUELLER.
